UNITED STATES PATENT OFFICE.

WILLIAM C. PAGE, OF OCEANPARK, CALIFORNIA.

SHOVEL.

Application filed July 3, 1922. Serial No. 572,499.

To all whom it may concern:

Be it known that I, WILLIAM C. PAGE, a citizen of the United States, residing at Oceanpark, in the county of Los Angeles and State of California, have invented a new and useful Shovel, of which the following is a specification.

This invention relates to power shovels especially designed for heavy work such as ditch digging, road making or the like.

The primary object of the invention is to provide a device of this character including an adjustable boom, novel means being provided for operating the boom in a horizontal plane.

Another object of the invention is to provide a shovel or machine of this character which may be readily and easily converted into a pile driving machine.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a side elevational view of a scooping shovel constructed in accordance with the invention.

Figure 2 is a fragmental detail view disclosing the means for securing the rotary table against lateral movement.

Figure 3 is a plan view of the scoop shovel.

Figure 4 is a sectional view through the pile driver guide.

Figure 5 is an elevational view disclosing the upper end of the pile driver guide and illustrating the manner of supporting the same.

Figure 6 is a front elevational view of the power shovel disclosing the same as employed as a pile driver.

Figure 7 is a sectional view taken on line 7—7 of Figure 1.

Figure 8 is a fragmental sectional view

disclosing the manner of supporting the beam support.

Figure 9 is a fragmental sectional view disclosing the manner of supporting the upper extremity of the beam support. 55

Figure 10 is an elevational view showing the shovel support and manner of securing the same, the supporting beam being shown in section.

Figure 11 is a fragmental sectional view 60 disclosing the connection between the uprights and the supporting members.

Referring to the drawings in detail, the reference character 5 designates a base which is preferably circular in formation, 65 to which base are secured horizontally disposed bars 6 that extend rearwardly and are connected at their rear ends by the weighting element 7 designed to counter-balance the uprights and hold the same in 70 their vertical positions, when the shovel to be hereinafter more fully described, is being operated.

Pivotedly supported on the base 5 is an auxiliary base 8 which is also circular in 75 formation and connected to the base 5 as by means of the pivot pin 9 disposed substantially centrally thereof. Secured to the auxiliary base 8 are the horizontal bars 10 which extend rearwardly and overlie the 80 bars 6, the free ends of the bars 10 terminating short of the ends of the bars 6, where they support the weight 11 which also tends to hold the device in an upright position. 85

A guide member indicated at 12 and formed with right angled extremities 13, clamps the bases 5 and 8 together in a manner to permit of movement of the auxiliary base 8 with respect to the base 5, 90 but at the same time restrict lateral movement and prevent tilting of the base 8 under the strain of the load carried by the shovel. Uprights 14 are connected to opposite sides of the auxiliary base 8, and have their upper ends connected by means of the cross bars 15, the capping bar 16 being secured to the extreme upper ends of the uprights 14, where the same supports the pulley 17.

Angularly disposed bracing beams 18 100

have their upper ends connected to the uprights 14, and have their lower ends connected to the bars 10 as at 19, whereby the uprights 14 are further supported and held in their upright positions, with respect to the bars 10.

The boom support is in the form of a swinging frame embodying uprights 20 spaced apart, the lower ends thereof, being secured to the swinging base 21 carrying the pivot pin 22 that extends through a suitable opening in the bases 5 and 8. The uprights 20 are connected to the base 21 as clearly shown by Figure 1 of the drawings. 15 A winch 23 is also positioned on the swinging base 21 to counterbalance the action of the weight of the load supported by the boom, and operates the flexible member.

The upper ends of the uprights 14 are 20 connected by means of the bar 24, which bar supports the pivot pin 25 that extends through a suitable opening in the capping bar 16, so that the frame may pivot in a horizontal plane permitting the shovel to 25 be moved to various angles with respect to the bases 5 and 8. Pivotedly connected to the base 21 is a boom embodying spaced bars 26, which have their upper ends connected as by means of the member 27 to 30 which the pulleys 28 are connected. The pulleys 29 which are connected to the opposite sides of the boom accommodate the flexible members 30 which also move over the pulleys 31 supported by the forward bar 15, as 35 clearly shown by Figure 1 of the drawings.

The shovel forming an important feature 40 of the invention includes a supporting arm 32 which is formed with side members providing a chute or trough to direct material 45 dislodged by the shovel or scoop 33 to the receiving trough 34 supported at the rear end of the arm 32.

This supporting arm 32 is hingedly supported by means of the swinging frame as 45 by means of the supporting member 35, the rear end of the supporting arm 32 extending an appreciable distance beyond the uprights 14 where the same overlies the receiving 50 trough 34 to discharge material thereinto.

The scoop or shovel, which is pivotally connected to the outer end of the arm 32 has upwardly extended arms 36 that support pulleys 37 over which the flexible connecting member 38 operates, the flexible connecting member 38 also moving over the pulleys 28 where the same extends to a point adjacent to the base 21 and passes over the drum not shown, of the winch 23.

60 The flexible member 30 also extends downwardly and is positioned over a suitable drum forming a part of the motor controlled winch 23. Supported at one side of the arm 32 is a weight controlled latch member 39

that cooperates with the lug 40 carried by 65 the scoop or bucket 33, which latch member is designed to hold the scoop 33 in a carrying position, when the arm and boom have been moved upwardly, thereby preventing the scoop 33 from discharging its contents prior 70 to the movement of the same to a discharging position. A controlling rope 41 has connection with the latch member 39 and is adapted to be operated at a predetermined period to release the scoop and permit the 75 same to discharge its contents into the arm 32 or trough.

The receiving trough 34 is provided with an auxiliary bottom 42 which is formed with 80 openings 43 that are covered by the screening elements 44, whereby the trough is divided into an upper compartment and a lower compartment, the heavier or larger stones passing through the upper compartment where they are discharged into a suitable receiver, while the finer grade of stone or material passes from the lower compartment into a suitable receiving member placed thereunder.

A platform indicated at 50 overlies the 90 bars 10, and affords means to permit wagons to be driven under the receiving chute to receive material therefrom.

While I have shown and described the invention as a machine especially designed as 95 a scoop shovel for digging trenches, ditches or the like, it is to be understood that by removing the arm 32, a pile driving guide which is indicated at 45 may be supported by the uprights 14 in a manner as clearly 100 shown by Figure 6 of the drawings.

The pile driving guide is relatively long and includes opposed sections 46 and 47, which sections are connected as by means of 105 the bolts 48 so that the sections may be disconnected and the driving medium, which is in the form of an elongated weight, placed therein. The pulley 17 accommodates the flexible member 49 that has connection with the driving element not shown, the flexible member 49 moving over the pulley and having its lower end connected to a suitable drum carried by the winch 23 or power device.

Having thus described the invention, what 115 is claimed as new is:—

An excavating machine including a stationary base, a rotatable base mounted at one end of the stationary base, a guide member secured to the stationary base and having a right angled end adapted to overlie a portion of the rotatable base, uprights carried by the rotatable base and having a pulley mounted adjacent to the upper end thereof, spaced bars mounted on the rotatable base and adapted to swing vertically, a scoop supporting arm pivotally mounted between the uprights and adapted to swing 120 125

vertically, a flexible member having connection with the spaced bars for moving them vertically, a scoop on the scoop supporting arm, a flexible member connecting the scoop and the upper end of the vertically swinging bars for adjusting the scoop with respect to the swinging bars, and a flexible member for connecting the vertically swinging bars to the uprights for adjusting the

vertically swinging bars and scoop with respect to the uprights. 10

In testimony that I claim the foregoing as my own, I have hereto affixed my signature in the presence of two witnesses.

WILLIAM C. PAGE.
